UNITED STATES PATENT OFFICE.

MARVIN W. REED, OF SOUTH FORK, PENNSYLVANIA.

THERMOMETER-CASE.

No. 918,472.

Specification of Letters Patent.

Patented April 13, 1909.

Application filed November 13, 1908. Serial No. 462,528.

To all whom it may concern:

Be it known that I, MARVIN W. REED, a citizen of the United States of America, residing at South Fork, in the county of Cambria and State of Pennsylvania, have invented new and useful Improvements in Thermometer-Cases, of which the following is a specification.

This invention relates to a casing for clinical thermometers of the type commonly used by physicians and professional nurses in taking the temperature of patients, the object of the invention being to provide a casing in which one or more thermometers may be carried in a secure manner, and which is adapted to contain a germ destroying solution in which the tips and adjacent portions of the thermometers are immersed, whereby the thermometers may be sterilized and kept in a thoroughly aseptic condition, thus preventing any possibility of transmitting disease germs from the mouth of one patient to another even in the event of the imperfect sterilization of the instrument after use and before it is restored to the casing.

The invention consists of the features of construction, combination and arrangement of parts hereinafter fully described and claimed, reference being had to the accompanying drawing, in which:—

Figure 1 is a side elevation of a thermometer casing embodying my invention as arranged to be carried in the pocket and secured to the person. Fig. 2 is a longitudinal section of the same. Fig. 3 is a section showing a detail of construction.

Referring to the drawing, 1 designates a casing of suitable size and form to fit within a vest or waist pocket, and preferably constructed of aluminum or other suitable material. The interior of this casing is divided by two parallel vertical longitudinal partitions 2 to form a pair of outer chambers 3 for the reception of a pair of ordinary clinical thermometers 4, and an intermediate chamber or compartment 5 forming a reservoir for a store or charge of a suitable germicide or antiseptic solution, such as peroxid of hydrogen or permanganate of potassium of proper strength, the use of which solutions is preferred, as they will not act chemically upon the material of which the casing is composed.

The germicide reservoir 5 terminates at its upper end a distance slightly below the cen-

ter of the casing and is closed by a transverse head or partition 6, through which opens the lower end of a filling tube 7, opening at its upper end through the top of the space or chamber 8 between the upper portions of the thermometer chambers and above the reservoir 5 and separated from the latter by the said partition 6, the said upper end of the tube being internally threaded to receive a threaded cap or closure 9.

The thermometers 4 are of the ordinary type in common use among physicians and professional nurses, and fit at their upper ends within hollow screw caps 10 which close the upper internally threaded ends of the chambers 3, whereby, when the thermometers are contained within the casing, the chambers will be closed against the access of foreign substances and the escape of the germicide solution in the event of the casing being accidentally inverted.

The storage reservoir 5 is in communication with the upper and lower ends of the thermometer chambers by way of ports or openings 11 and 12 formed in the partitions 2, thus allowing the germicide solution to circulate or flow back and forth from the storage compartment to the thermometer chambers to provide for its proper displacement from one to the other during the insertion and removal of the thermometers, as well as for the passage of air between the reservoir and chambers when the reservoir is being filled or the solution is passing back and forth to compensate for variations in the effective capacity of either chamber when the thermometer is inserted or removed. The tops and adjacent portions of the thermometers are designed to be immersed in the antiseptic solution in the bottom portions of the chambers, so as to destroy any bacteria which they may carry and to render and maintain them sterile while they are inclosed within the casing. As stated, the upper ends of the thermometers are fitted within the hollow caps 10. Each thermometer is preferably secured in its cap by glue or cement so that if it should be accidentally broken the adhering portion may be detached from the cap and another thermometer of the same size purchased and secured in its place.

The reservoir in practice is made but half the height of the thermometer chambers, or less, to prevent the antiseptic solution from rising sufficiently high in the thermometer

holders to cause an overflow when a thermometer is being placed in its position in either chamber before the solution can readjust itself to the level of the solution in the reservoir. The reservoir may be emptied and replenished at desired intervals with a fresh charge of the solution by unscrewing the cap 9 and supplying the fresh solution through the tube 8. In this operation, one of the thermometers is partially removed by unscrewing its cap 10 and slightly elevating the thermometer so as to allow a free passage for the exit of the air from the storage chamber displaced by the entering liquid. This will also prevent bubbling of the liquid through the tube to the reservoir in the filling operation. Any suitable fastening means may be employed to secure the casing to the vest, waist or other article of clothing of the wearer in order to guard against possible accidental loss or dropping of the same from the pocket. The fastening device shown in the present instance comprises a chain 13 secured at one end to the casing and carrying at its opposite or free end a safety pin 14 or the like for attaching the chain to the garment.

After using a thermometer in the customary manner to take the temperature of a patient, the physician or nurse may simply rinse the thermometer in a glass of water and replace it in the case, the antiseptic solution rendering it within a minimum proportion of time thoroughly sterile, so as to prevent any possibility of transmitting disease germs from one patient to another. Frequently a physician or nurse, through lack of time or care, fails to thoroughly clean a thermometer which has been used before restoring it to its casing, in which event there is always danger of the transmission of disease from one patient to another. My invention avoids this objection, as, even in the event of the imperfect prior sterilization of the instrument after use, any bacteria which may be carried thereby will be destroyed by the germicide solution as soon as it is restored to the casing.

Having thus fully described the invention, what is claimed as new is:—

50 1. A thermometer case comprising a flattened tube closed at its lower end, longitudinal partitions subdividing the interior of the tube to form thermometer compartments open at their upper ends and an interposed storage chamber for a germicide solution communicating at its upper and lower ends with said compartments, a filling attachment supported by the case and communicating with said storage chamber, and thermometers adapted to occupy the compartments

and provided with closures for the open ends thereof.

2. A thermometer casing comprising a flattened tube closed at its lower end and provided with spaced longitudinal partitions forming counterpart thermometer compartments open at their upper ends and an interposed germicide storage chamber between lower portions of one-half of the compartments, said chamber being in communication at its upper and lower ends with said compartments, a filling device arranged between the upper portions of the compartments and communicating with the storage chamber, thermometers adapted to fit within the compartments, and closures for said compartments carried by the thermometers.

3. A thermometer casing comprising a flattened tube closed at its lower end and subdivided to provide spaced thermometer compartments open at their upper ends and an interposed germicide storage chamber communicating with said compartments, a filling tube carried by the casing and communicating with said storage chamber, a removable closure for the tube, and thermometers adapted to fit within the compartments and provided with screw caps to close the open ends thereof.

4. A thermometer casing provided with a pair of thermometer chambers, and a storage chamber for a germicide solution disposed between the thermometer chambers and terminating below the upper ends of the latter, said storage chamber being in communication at its upper and lower ends with the thermometer chambers, and a filling tube extending down between the upper ends of the thermometer chambers and in communication at its lower end with the storage chamber, said tube having a suitable closure.

5. A thermometer casing having thermometer receiving chambers, hollow screw caps for closing said chambers, a storage reservoir for a germicide solution arranged between the lower ends of the receiving chambers and in communication at its upper and lower ends therewith, a filling tube in communication at its lower end with the storage chamber and extending upwardly between the receiving chambers, a closure for the upper end of said tube, and thermometers adapted to fit within the receiving chambers and secured within the said screw caps.

In testimony whereof I affix my signature in presence of two witnesses.

MARVIN W. REED.
